UNITED STATES PATENT OFFICE.

HORATIO G. GILLMOR, OF WASHINGTON, DISTRICT OF COLUMBIA.

RAIL-ANCHOR.

1,297,460.

Specification of Letters Patent. Patented Mar. 18, 1919.

Application filed November 7, 1916. Serial No. 130,050.

To all whom it may concern:

Be it known that I, HORATIO G. GILLMOR, a citizen of the United States, residing at Washington, in the District of Columbia, 5 have invented certain new and useful Improvements in Rail-Anchors, of which the following is a specification.

My invention relates to a device for preventing the longitudinal movement of the 10 rails of railways, generally known as creeping, and devices of this sort are commonly called rail anchors, rail stays or anticreepers. The principal object of the invention is to provide a device of this character 15 which will be very simple in construction, inexpensive to manufacture and easily applied, using the tools ordinarily employed by railway track workers.

Further objects of the invention are to 20 provide a device which will take a very firm and reliable grip upon the rail and shall have efficient means for maintaining the grip of the device upon the rail as against disturbing influences such as vibration, contraction and expansion of the 25 metals due to changes of temperature and tendency of the rail to move at times in a direction the reverse of the direction in which the rail would move under the forces 30 causing creeping.

The invention has for further objects such other new and improved constructions, arrangements and devices relating to devices for preventing the longitudinal creep of rail- 35 road rails as will be hereinafter described and claimed.

A preferred embodiment of the invention is illustrated in the accompanying drawings, in which:—

40 Figure 1 is a view of the device applied to the rail, looking toward the tie and showing the rail and one of the parts of the device in section.

Fig. 2 is a side elevation of the device in 45 operative position on the rail.

Fig. 3 is a view of the device, looking away from the tie showing one of the positions of the parts while being applied to the rail, illustrating the method of applying the 50 device.

Fig. 4 is a perspective view of the dog or pressure producing part.

Fig. 5 is an end view of the transverse part of the device.

55 Like characters of reference designate like parts in the several figures of the drawings.

Referring to the drawings A represents a railroad rail having a base flange B and C a portion of one of the ties, upon which it rests and is supported.

The device of my invention preferably 60 consists of two parts or elements D and E shown separately in Figs. 4 and 5, respectively.

The element D which may be made from a 65 flat bar or plate, is constructed to be applied to the rail and the element E to produce a vertical pressure and cause the rail to be gripped between the elements D and E. It is provided with a portion F which 70 forms an arm having a surface G, which, with the device in operative position on the rail, engages and presses down upon the upper surface of the rail base; and a surface H somewhat rounded. The upper part 75 of the body of the element D has a surface I and at the lower end of the element D there is a portion K which forms an arm having a surface L; which, with the device in operative position on the rail, engages the 80 element E and a surface M. The portion K is also provided with a projection N, which engages a wrench when removing the device from the rail.

The element E is applied transverse to the 85 rail and has at one end a jaw C adapted to engage the base flange B of the rail A at one side of the rail and at the other end has shoulders P which are adapted to engage the vertical edge of the rail base B 90 opposite the jaw O. The portion Q of the element E is curved as shown by the dotted lines in Fig. 2 and illustrated more fully in Fig. 5, so that the normal condition of the element E presents a concave surface to the 95 rail bottom adjacent, and for some distance in from, the shoulders P. Projecting from the portion Q of the element E, downward, there is a portion R, which has a bearing portion S between two projections or guiding flanges T. Between the jaw O and the shoulders P the element E has a portion U adapted to engage a face of the tie C. The jaw O and other portions of the element E may be strengthened by flanges V. 100

In dotted lines in Fig. 1 there is indicated a wrench for removing the element D when it is desired to remove the device from the rail.

110 In applying the device to the rail the element E is applied transverse to the rail with the jaw engaging the base flange B of the

rail A, at one side, and the element E is then forced transverse to the rail until the shoulders P will be in a position to engage the vertical edge of the base flange B. For 5 rails which are of normal width of base or of less than normal width (normal width referring to the standard designed width of base for a rail of any size) when this position is reached there will be a narrow space 10 Y between the vertical edge of the rail base and the throat of the jaw O, as illustrated in Figs. 1 and 3. If the rail is wider on the base than the standard designed width of the rail, the element E may have to be 15 forced onto the base flange B until there will be no space between the throat of the jaw O and the vertical edge of the base flange B. In this way considerable variation in dimension of the base flange B from the 20 designed dimensions for any given size of rail will still not prevent the proper application of the device to the rail. When the element E is in the position in which the shoulders P may be brought into engagement 25 with the edge of the base flange B, the element D is placed with the arm F engaging with the rounded surface H the upper surface of the base flange B and the surface M of the portion K engaging the bearing S 30 between the guiding flanges T of the element E and is forced transverse to the rail until the surface I contacts with the edge of the rail base flange B between the shoulders P. In this way a vertical stress is ex- 35 erted upon the element E the first effect of which is to draw the end of the element E upward so that the shoulders P are brought into engagement with the edge of the base flange B so as to hold the element E in position. This position of the parts during 40 application of the device is illustrated in Fig. 3 and with the parts in this position the portion Q of the element E may contact with the rail bottom immediately adjacent 45 the shoulders P but will stand away from the rail bottom about as indicated by the dotted lines in Fig. 2. The element D is now forced to its final position by forcing the arm K, by driving with a hammer or 50 maul or in some other suitable manner, toward the rail; and, during this movement of the element D, the arm F rolls on the surface H on the upper surface of the rail base B until the surface G comes into con- 55 tact with the upper surface of the rail base flange B, and the arm K moves over the bearing S of the element E guided in a plane transverse to the rail by the guiding projections or flanges T until the surface L 60 of the element D engages the bearing S of the element E fully. The effect of this forced movement of the element D is to put further vertical stress upon the rail and the element E and, under this stress the portion 65 Q, which normally presents a surface con-

cave to the rail bottom, is straightened out and drawn flat against the rail bottom, as illustrated by the full lines in Fig. 2. In this way the element E is made to bear with increasing pressure upon the rail bottom 70 and the pressure of the element E upon the rail base B is distributed over the whole of the portion Q and for a considerable distance away from the edge of the rail base B. The final operative position of the parts 75 of the device upon the rail is illustrated in Figs. 1 and 2 and it will be readily seen that, with the parts in this position, the device is effectively locked upon the rail and the rail firmly and reliably gripped by the 80 device. The arm F of the element D cannot be disengaged from the rail base except by movement of the element D in a direction the reverse of the movement in applying, which movement is opposed by the 85 weight of the element D and by the great friction opposing such movement.

When the rail moves under forces producing creep, it carries the device with it until the portion U of the element E comes in contact with the face of the tie C when the engagement of U with the tie, which is held in the ballast and, therefore, a fixed portion of the roadbed, prevents further forward movement—that is, movement in the direction of 95 creep, indicated by the arrow in Fig. 2. If for any reason the grip of the device upon the rail should not be sufficient to withstand the forces tending to produce creep after the portion U of the element E 100 is in contact with the tie and some movement of the rail in relation to the element E were produced by the creeping forces such movement will cause a slight canting of the element D as shown in dotted lines in Fig. 105 2, the arm F being carried forward with the rail and this slight canting or angular movement of the element D will automatically increase the grip of the parts upon the rail so that the creeping will be self checked. 110

It will be readily seen that the part E is effectually locked upon the rail base B by the engagement of the jaw O and the shoulders P with opposite edges of the base flange B and the engagement of the element D 115 with it and the rail base B and the resiliency of the portion Q of the element E and of the element D prevents these elements from being affected by vibration or other accidental cause. Moreover, should the rail be caused by changes of temperature or other reason to move backward, such reverse movement would be without effect upon the grip of the device upon the rail even though the element were held in frozen ballast or otherwise prevented from moving in the reverse direction with the rail.

It will also be readily understood that the device can be applied to the rail using only a maul or other tool usually carried by track 120 125 130

workers and that when once applied it cannot be removed with the same tools without destruction of one or both of the parts. This prevents the accidental or unauthorized removal of the device. To provide for the ready removal, when removal of the device is desired, a wrench similar to that shown in dotted lines in Fig. 1 may be employed. The wrench engages the projection 5 N of the element D and its body so that movement, the reverse of the movement by which the element D was forced into position, may readily be produced and the element D removed, which will permit the element E to be at once removed.

While the invention has been shown and described in a preferred embodiment, it will be understood that modifications might be made without departure from the principles 10 of the invention. Therefore I do not wish to be understood as limiting the invention to the exact constructions and arrangements shown and described except so far as the claims are specifically so limited.

25 I claim and desire to secure by Letters Patent:

1. A vertical pressure producing part for rail anchors constructed from a flat bar and provided with two arms adapted so to engage 30 the upper surface of the rail base flange and a groove in the bottom of a rail base engaging part that said first part may be forced into position by angular movement of said part about axes lying above the rail 35 base.

2. A vertical pressure producing part for rail anchors constructed with two arms, one of which is adapted to engage the upper surface of the rail base and to roll thereon when 40 said part is being forced into position and the other of which is adapted to so engage a rail base engaging part that when in position said pressure producing part may move angularly about an axis transverse to the 45 rail.

3. A transverse part for rail anchors constructed with rail base edge engaging means at one end thereof and with a shallow trough shaped portion on the upper side and with a 50 seat adapted to engage a pressure producing part on the under side of the other end thereof.

4. A clamping part for anticreepers comprising a rail base engaging jaw at one end 55 and rail base edge engaging portions at the other end connected by a transverse portion, presenting normally a concave surface to the rail bottom, provided with a seat below the rail and adjacent the rail edge engaging 60 portions adapted to engage a pressure producing part.

5. An anticreeper for rails, comprising a rail gripping element, one end of which is 65 trough shaped on the upper side thereof and is provided with a retaining catch and the

other end thereof is constructed with rail base engaging means, and a rail engaging device for drawing the trough shaped portion into contact with the rail bottom and the retaining catch into engagement with 70 the rail base edge.

6. A rail anchor, comprising a rail gripping element having at one end a rail base engaging jaw and at the other end a retaining catch and a concave surface on the upper side thereof and a seat on the lower side thereof, a rail engaging device, for drawing the concave surface into contact with the rail bottom, and means for giving one of 75 said parts a fixed position in the roadbed in opposition to the tendency of the rail to creep.

7. In a rail anchor, a rail base flange engaging and gripping element and a rail engaging device so engaging the rail base 85 above and said element below the rail as to permit angular movement of said device about a longitudinal axis above and a transverse axis below the rail base.

8. A device for preventing the creeping of 90 rails, comprising a rail embracing and gripping part, a rail engaging pressure producing device so engaging the rail base above and said part below the rail bottom as to be rotatable about a longitudinal axis above the 95 rail base and about a transverse axis below the rail base, and means for engaging a tie.

9. A rail anchor, comprising a rail gripping member provided with a tie engaging portion and a rail engaging device so pivoted 100 upon the upper surface of the rail base and upon said rail gripping member below the rail as to be adapted to move angularly about two axes at right angles the one to the other, one above and the other below the rail 105 bottom, for effecting the gripping action.

10. An anticreeper, comprising a transversely extending part engaging the top and the bottom of the rail foot flange at one side of the rail and the bottom of the rail at the 110 other side of the rail, and a vertically extending part so engaging the rail base above and said transversely extending part below the rail as to permit angular movement of said vertically extending part about a longitudinal axis above the rail to force said vertically extending part into position and to permit angular movement of said vertically extending part about a transverse axis below the rail when in position.

11. An anticreeper, comprising two rail gripping elements, one of which is provided with means for engaging a fixed portion of the road bed in opposition to the tendency of the rail to creep, and one of which comprises a flat bar formed with a cam-shaped arm adapted to engage and roll upon the upper surface of the rail base flange and with an arm adapted to engage with the other element below the rail base.

12. An anticreeper, comprising a transversely extending part engaging the top and bottom of the rail foot flange at one side and the edge of the rail foot flange at the other side of the rail and provided with a seat adjacent the edge engaging end of said part below the rail and with a tie abutting portion and a pressure producing element so engaging the upper surface of the rail base 10 that rotation of said element in a plane transverse to the rail will force said element into engagement with said part, causing said transversely extending part to grip the rail at opposite sides, and that angular 15 movement of the rail in relation to said transversely extending part will produce angular movement of said vertically extending element and automatically increase the grip of the device upon the rail.
13. A rail anchor, comprising a bottom engaging part constructed to bear upon the bottom and one edge of the base of a rail and a vertical pressure producing part adapted so to engage the rail base above and 20 said bottom engaging part below the rail bottom that said pressure producing part may be rotated transversely about an axis above the rail base when being forced into position and, when in position, move angularly about 25 a transverse axis below the rail base, one of said elements being provided with means for giving it a fixed position in the roadbed as against the tendency of the rails to creep.
14. A rail stay, comprising an element engaging the top of the rail base flange at one side and the edge of the rail base flange at the other side and the bottom of the rail base between the edges thereof and a part provided with means for engaging rotatably with the 30 upper surface of the rail base and with an arm engaging with said element below the rail base, said element being provided with means for giving the same a fixed position in the roadbed as against the tendency of the rails to creep.
15. An anticreeper, comprising a rail gripping member arranged for transverse disposition beneath the rail and provided with a rail base flange gripping portion at one end 35 and a rail base edge engaging portion at the other end and with a tie abutting portion intermediate the flange gripping and base edge engaging portions thereof and a vertical pressure producing part arranged to engage 40 rotatably with the rail base above and with the rail gripping member below the rail bottom for effecting the gripping action.
16. A device for preventing the creeping of rails, comprising a rail engaging and 45 gripping element provided with a jaw adapted to engage the rail base flange at one side of the rail a transverse portion provided with a tie engaging flange and a grooved seat, said transverse portion being so formed 50 as to present normally concave surface to the under side of the rail and a vertical pressure producing part engaging the rail base above and said gripping element below the rail bottom and drawing the normally concave surface of said element up into contact 70 with the rail bottom.
17. An anticreeping device for rails, comprising a rail embracing and clamping element arranged to engage the base flange at opposite sides of the rail and to present normally a concave surface to the rail bottom, a transversely disposed vertical pressure producing part engaging the upper surface of the rail base and said clamping element and drawing the normally concave surface thereof up into contact with the rail bottom and means for giving one of the elements a fixed position in the roadbed as against the tendency of the rails to creep. 75
18. A rail anchor, comprising a tie engaging rail gripping element arranged for transverse disposition beneath the rail and having one end bowed downwardly in the direction of length of the rail and a vertical pressure producing part so engaging the rail base above and said element below the rail bottom that transverse movement of said pressure producing part in relation to the rail will draw the downwardly bowed portion of said element up against the rail bottom. 80
19. A rail anchor, comprising a rail engaging element arranged for transverse disposition beneath the rail engaging at one side of the rail the upper surface of the base flange and at the other side the edge of the 85 base flange and presenting normally a curved surface to the rail bottom adjacent the rail edge, a part engaging the rail base above and said element below the rail and arranged to be forced transversely to the rail for drawing the curved surfaces of said element into contact with the flat bottom of the rail and effecting the gripping action of the device, and tie engaging means for holding one of 90 said elements in fixed position in the roadbed as against the tendency of the rail to creep. 95
20. An anticreeping device, comprising a rail embracing element provided with means for giving said element a fixed position in the roadbed as against the tendency of the rails to creep constructed to engage the top and bottom of the rail base at one side and the edge of the rail base at the other side of the rail and a vertical pressure producing 100 part so engaging the upper surface of the rail base and said rail embracing element below the rail that transverse rotational movement of said part about the rail base will effect the gripping action of the device. 105
21. A device for preventing the creeping of rails, comprising a transversely disposed part constructed to engage the top and bottom of the rail at one side and the 110
- 115
- 120
- 125
- 130

edge of the rail base at the other side and to engage a tie intermediate of the rail edges, and a pressure producing part, arranged to be forced into position by transverse rotation about the rail base, engaging the rail base above and said transversely disposed part below the rail and to automatically increase the grip of the device upon the rail by angular movements of said pressure producing part produced by slight movement of the rail longitudinally in relation to said transversely disposed part.

22. A rail anchor, comprising a rail gripping element, a part formed from a flat bar so engaging the upper surface of the rail base above and said gripping element below the rail bottom at the side of the rail opposite to said gripping element that said part may be forced into position by transverse movement and rotation about axes above the rail base and when in position may move about an axis below and transverse to the rail, and means giving the lower end of said part a fixed position in the road-bed in opposition to the tendency of the rail to creep.

23. A rail stay, comprising a flange gripping and bottom engaging element provided with a tie-engaging portion, and a flat bar formed so as to engage with the rail base flange above and said bottom engaging element below the rail base that said bar may be forced into position by transverse and angular movement about axes above the rail base and that movement of the rail in relation to said flange gripping and bottom engaging element will cant said bar and thereby increase the grip of said flange and bottom engaging part upon the rail.

24. An anticreeper, comprising two rail gripping elements, one of which is provided with a tie-engaging portion, and one of which comprises a part formed from a flat plate and having a cam-like arm engaging the rail base above and a sliding arm engaging the other element below the rail bottom and which presses said other element up against the rail base.

25. A rail anchor, comprising two rail engaging and gripping elements, one of which is formed with means for giving the device a fixed position in the roadbed as against the tendency of the rail to creep, one of which is constructed to be applied transversely to the rail and to engage the rail bottom initially at the forward and rearward edges thereof and to be out of contact with said rail bottom between the edges of said element, and one of which embraces one edge of the rail base and one end of the other of said elements and clamps the rail between them.

26. An anticreeper, comprising two parts, one of which is a transverse bar engaging opposite edges of the rail base and at the

two edges of said bar the bottom of the rail base with a surface intermediate of said edges which is normally out of contact with the rail bottom, and a part which embraces one side of the rail base and the other part 70 and exerts pressure thereon, one of said parts being provided with tie-engaging means.

27. A rail anchor, comprising two rail gripping elements, one of which is formed with a tie-engaging flange, engages the rail base at one side of the rail, extends transversely beneath the rail, engages the edge of the rail base and at the edges of said element the rail bottom while normally out of contact with the rail bottom between the edges of said element at the other side of the rail, and the other of which comprises a bar which engages said element and the upper surface of the rail base and is arranged to 80 be forced into position by transverse angular movement in relation to the rail.

28. A device for preventing the creeping of rails, comprising two rail gripping members, one of which is formed to engage a 90 fixed portion of the roadbed in opposition to the tendency of the rail to creep and comprises a transverse element engaging the rail base at opposite sides of the rail and presenting to the rail bottom a surface between the edges thereof normally out of contact with the rail bottom at one end thereof, and the other of which is a clamp engaging the rail base above and said element below the rail to draw and hold said element up 100 against the rail bottom.

29. A rail anchor, comprising two rail engaging and gripping parts, one of which is a member embracing the rail base at one side of the rail and extending transversely 105 beneath the rail with an upper surface which is concave, and the other of which is a bar which so engages the rail base above and said part below the rail bottom as to permit angular movement of said bar about said part.

30. A device for preventing the creeping of rails, comprising a clamp constructed to embrace one side of the rail base, and a transverse part which engages the rail base at the other side of the rail and has a portion presenting normally a concave surface to the rail bottom and which intervenes between the rail bottom and said clamp, one of said parts having means for engagement 115 120 with a fixed portion of the roadbed.

31. A rail anchor, comprising a clamp constructed to embrace one side of the rail base, and a transverse part provided with a tie engaging portion which engages the rail 125 base at the other side of the rail and has a portion presenting a normally concave surface to the rail bottom and which intervenes between the rail bottom and said clamp.

32. A rail anchor, comprising a transverse

element one end of which engages the rail base at one side of the rail and the other end of which is provided with a trough shaped portion on the upper side thereof, a clamp 5 which engages said element below and the base of the rail above the bottom of the rail at the other side of the rail, and tie-engaging means operative upon one of said elements.

33. An anticreeper, comprising a trans- 10 verse element having at one end a jaw engag- 15 ing the rail base at one side of the rail and upon the upper side of the other end a trough shaped portion and a rail base edge engaging portion, and a pressure producing part engaging the upper surface of the rail 20 base and said element at the other side of the rail and pressing said element against the rail base, one of said elements being pro- 25 vided with a tie-engaging portion.

34. A rail anchor, comprising a clamp embracing the rail base at one side of the rail, and a transverse part having a concave upper surface which intervenes between the clamp and the rail bottom and engages the 25 rail base at the other side of the rail and is provided with a tie-engaging flange.

35. A rail stay, comprising a clamp engag- 30 ing the upper surface of the rail base at one side of the rail and a transverse part provided with a shallow trough-like upper surface which intervenes between said clamp and the rail bottom, engages the edge of the rail base, embraces the other side of the rail base and is provided with means for engag- 35 ing a fixed portion of the roadbed in opposition to the tendency of the rail to creep.

36. An anticreeper, comprising a part formed at one end with an arm adapted to engage the upper surface of the base flange 40 at one side of the rail and at the other end with a shallow trough shaped portion and rail base edge engaging portions, and a clamp adapted to engage said part below and the rail base above the rail bottom, one 45 of said elements having a tie-engaging portion.

37. An anticreeper, comprising a part formed at one end with an arm adapted to engage the upper surface of the base flange 50 at one side of the rail and at the other end with rail base edge engaging portions, a clamp formed from a flat bar constructed to engage the rail base above and said part below the rail bottom and to be forced into 55 position by angular movement about axes above the rail base, and means operative upon the lower end of said part to give it a fixed position in the roadbed.

38. An anticreeper, comprising a part 60 formed at one end with a jaw adapted to engage the rail base at one side of the rail and at the other end with a portion adapted to engage the edge of the rail base at the other side of the rail and provided with 65 means for giving said part a fixed position

in the roadbed in opposition to the tendency of the rail to creep, and a clamp formed from a flat plate adapted to engage said part below and the rail base above the rail bottom at one side of the rail and to be forced into position by transverse angular movement in relation to said part about axes lying above the rail base.

39. A rail anchor, comprising a trans- 75 versely extending part engaging the edge and bottom of the rail base at one side of the rail and embracing the other side of the rail and a vertically disposed flat plate formed so to engage the rail base above and said transversely extending part below the 80 rail bottom that said plate may be forced into position by transverse angular movement about axes lying above the rail base, and means operative upon the lower end of said plate to hold said lower end in opposition to the tendency of the rail to creep. 85

40. A device for preventing the creeping of rails, comprising a rail embracing and gripping part and a rail engaging pressure producing device constructed from a flat 90 bar which is so connected to said part as to be rotatable about longitudinal axes lying above the rail base and about an axis transversely disposed in relation to the rail lying below the rail base. 95

41. A rail anchor, comprising a rail gripping element embracing the rail base flange at one side of the rail and provided with a catch projection adapted to engage the rail base at the other side of the rail, a trough 100 shaped portion adjacent to said catch projection, and a tie-engaging portion, and a rail engaging device pivotally engaging said element and the rail base for drawing the catch projection into contact with the edge 105 of the rail base flange and the trough shaped portion into contact with the bottom of the rail base flange.

42. A rail anchor, comprising a rail gripping element embracing the base flange at 110 one side of the rail and provided with a catch projection adapted to engage the rail base flange at the other side of the rail, and a rail engaging device engaging said element and engaging rotatably the upper 115 surface of the rail base for drawing said catch projection into contact with the edge of the rail base flange.

43. An anticreeper, comprising a rail gripping element embracing the base flange 120 at one side of the rail and provided with catch projections adapted to engage the base flange at the other side of the rail, a rail engaging device engaging said element and engaging rotatably the upper surface of the 125 rail base for drawing said catch projections into contact with the edge of the rail base flange, and means for giving one of said elements a fixed position in the roadbed.

44. A rail anchor, comprising a rail em- 130

bracing element constructed to engage the top and bottom of the base of the rail at one side of the rail and the edge of the base flange of the rail at the other side of the 5 rail, a vertical pressure producing part, formed from a flat bar, arranged to engage rotatably with the base flange above the rail bottom and to engage said element below the rail bottom, and means for giving 10 the device a fixed position in the roadbed.

45. A rail anchor, comprising a rail base engaging part constructed with a jaw at one end, a base edge engaging portion and a trough shaped portion at the other end 15 thereof, and a rail base engaging pressure producing element constructed with a bearing surface so co-acting with the bearing surface of said part that transverse angular movement of said element will force said

element into position and effect the gripping 20 action of the rail.

46. A device for preventing the creeping of rails, comprising two rail gripping elements, one of which is formed with means for engaging a fixed portion of the roadbed 25 in opposition to the tendency of the rail to creep and has a jaw engaging the rail base at one side of the rail and a portion engaging the edge of the rail base at the other side of the rail, and one of which comprises 30 a plate for rotatably engaging the upper surface of the rail base and for bearing upon said element first named below the rail base to draw and hold said element up against the rail bottom with said base edge engaging portion in engagement with the edge of 35 the rail base.

H. G. GILLMOR.
